1,332,750.

M. L. PIERCE,

PINCUSHION,

APPLICATION FILED JUNE 14, 1918.

Patented Mar. 2, 1920.

Fig. 1.

Fig. 2.

Inventor:

Mary L. Pierce.

Witnesses.

F. B. Gibson.
J. Williams

By Victor J. Evans
Attorney.

UNITED STATES PATENT OFFICE.

MARY L. PIERCE, OF MARLBORO, MASSACHUSETTS.

PINCUSHION.

1,332,750.

Specification of Letters Patent. Patented Mar. 2, 1920.

Application filed June 14, 1918. Serial No. 240,037.

To all whom it may concern:

Be it known that I, MARY L. PIERCE, a citizen of the United States, residing at Marlboro, in the county of Middlesex and State of 5 Massachusetts, have invented new and useful Improvements in Pincushions, of which the following is a specification.

This invention relates to improvements in pin cushions, the object of the invention being to provide an improved pin cushion which embodies a core figure which adds greatly to the attractive appearance of the cushion and also serves to preserve the form of the cushion.

Another object of the invention is to provide an improved pin cushion of this kind with a holding frame which serves to increase the attractive appearance of the pincushion and also enables the same to be readily hung up on any suitable supporting object.

With the above and other objects in view the invention consists in the construction and arrangement of parts hereinafter described and claimed.

In the accompanying drawing:

Figure 1 is a perspective view of a pair of pin cushions constructed in accordance with my invention and provided with a holding frame by means of which they may be readily suspended.

Fig. 2 is a sectional view of one of the cushions.

My improved pin cushion embodies a core figure 1, a stuffing 2, and a covering 3. In practice the core figure may be any suitable design and is here shown as a small doll. Any animal figure or other figure may be substituted and employed if desired in the 40 construction of my pin cushion and I would have it understood that I do not limit myself in this particular.

The stuffing 2 may be made of any suitable material, such as raw cotton or the like. The 45 covering 3 may be made of silk or any other suitable fabric. The covering is gathered around the core figure near the end of the core figure, as at 4. Hence in a cushion in which the core figure is a doll, as here shown, the head and feet of the figure will 50 project from opposite ends of the cushion. As here shown the hands of the doll also project from one side of the cushion. The covering may be made of any suitable fabric other than silk or satin if preferred and 55 may be of any suitable or desired color or shade.

I also in accordance with my invention provide a holder 5 which is here shown as a hoop and which is covered by a winding 6 60 of ribbon or the like.

In the embodiment of the invention shown in Fig. 1, two of the cushions are employed, as indicated at A and the cushions are arranged side by side and stitched to opposite 65 sides of the holder hoop and are also lightly stitched together. A ribbon band 8 extends across the center of the hoop and connects the upper and lower sides thereof and also passes between the cushions and is provided 70 at the upper side of the hoop with a bow or suitable knot 9.

The holder frame serves to greatly enhance the attractiveness of the cushion and also forms a supporting base therefor and 75 enables the cushion to be readily hung up if desired.

A single cushion may be employed in the holder frame or any suitable number of the cushions may be so employed as desired. 80

Having thus described the invention what is claimed is:

In a pin cushion, a hoop-like support, a band extending across the center of the hoop and connected to the upper and lower sides 85 thereof, cushions secured to the hoop, connected together and having their confronting ends contacted by the band, and each of said cushions having a core figure provided with offset portions the ends of which, 90 as well as the ends of the core figure extending through the cushion, and a stuffing in the cushion around the core figure.

In testimony whereof I affix my signature.

MARY L. PIERCE.